UNITED STATES PATENT OFFICE

116,849

DESIGN FOR A LAWN MOWER HOUSING

Marlowe H. Kluter, Richmond, Ind., assignor to The F. & N. Lawn Mower Company, Richmond, Ind., a corporation of Delaware

Application April 5, 1939, Serial No. 84,071

Term of patent 14 years

To all whom it may concern:

Be it known that I, Marlowe H. Kluter, a citizen of the United States of America, residing at Richmond, in the county of Wayne and State of Indiana, have invented a new, original, and ornamental Design for Lawn Mower Housing, of which the following is a specification, reference being had to the accompanying drawing, forming part thereof,

Figs. 1 and 2 are perspective views, taken from different angles, of a lawn mower housing embodying the design.

I claim:

The ornamental design for a lawn mower housing, as shown,
